DESIGN FOR A CONTAINER

William F. Schmalz, Rockville, Conn., assignor to Colt's Patent Fire Arms Manufacturing Company, Hartford, Conn., a corporation of Connecticut

Application December 6, 1937, Serial No. 73,401

Term of patent 14 years

To all whom it may concern:

Be it known that I, William F. Schmalz, a citizen of the United States, residing at Rockville, in the county of Tolland and State of Connecticut, have invented a new, original, and ornamental Design for a Container, of which the following is a specification, reference being had to the accompanying drawing, forming part thereof.

Of the drawing:

Fig. 1 is a bottom plan view of a container embodying the new design.

Fig. 2 is an elevational view of the container shown in Fig. 1, the container side walls being indicated in dot and dash lines.

Fig. 3 is an elevational view similar to that shown in Fig. 2 with a portion of the container broken away to show a section on the line 3—3 in Fig. 1.

The dominant feature of the design is found in the plurality of recesses and interspaced radially extending ribs in combination with the plurality of concentric serrations as shown in Fig. 1.

I claim:

The ornamental design for a container, as described and shown.

WILLIAM F. SCHMALZ.
